PERFORATOR FOR AUTOMATIC TELEGRAPHING.

No. 439,164.

Patented Oct. 28, 1890.

UNITED STATES PATENT OFFICE.

FRANK D. MACK, OF CHICAGO, ILLINOIS.

PERFORATOR FOR AUTOMATIC TELEGRAPHING.

SPECIFICATION forming part of Letters Patent No. 439,164, dated October 28, 1890.

Application filed July 13, 1889. Serial No. 317,485. (No model.)

To all whom it may concern:

Be it known that I, FRANK D. MACK, residing at Chicago, in the county of Cook and State of Illinois, and a citizen of the United States, 5 have invented a new and useful Improvement in Perforators for Automatic Telegraphing, of which the following is a specification, reference being had to the accompanying drawings, in which—

- 10 Figure 1 is a plan. Fig. 2 is a detail, being a section through the upper part of the machine, taken at line 2 2 of Fig. 1. Fig. 3 is a vertical longitudinal central section. Fig. 4 is a detail, being a front view of the plate 15 which receives the punches or pins and some other parts. Fig. 5 is a detail showing the arrangement of the perforating-pins. Fig. 6 is a side elevation showing two of the perforating-pins and bars to which they are attached. 20 Fig. 7 is a detail, being a side elevation of one of the sliding bars which act upon the cross-bars, which are secured to the sliding bars which carry pins.

This invention relates to apparatus for perforating paper in automatic telegraphing; 25 and the objects of the invention are to improve the prior mechanism and to provide novel means whereby the single depression of one key will produce the dots, dashes, and 30 spaces required for any one letter.

To accomplish these objects my invention involves the features of construction, the combination or arrangement of devices, and the principles of operation hereinafter described 35 and claimed.

In the drawings, 1 indicates a base; 2, a narrow front piece; 3, a rear piece, which forms part of the frame, and 4 a top piece, the center of which is cut out, which forms the 40 upper part of the frame, and is supported by the rear piece 3 and by two posts, one of which 5 is shown in Fig. 3, the other post being at the right-hand of the machine. Screws 6 pass through the part 4 into the posts 5.

45 7 are a number of keys or levers, of which, as shown, there are twenty-four. Each lever is provided with a finger-piece 8, each of which is used for a letter, except that the letter J is made by repeating the letter N, and the 50 letter L is made by combining the letters I and M. I have indicated on these keys the arrangement of the letters which I suppose

to be the most advantageous. Each key or lever 7 extends back, as shown, on a diagonal line to the rear of the machine, and is there 55 pivoted on a rod 9, which is supported in the frame, and from there each key or lever extends up vertically, and each vertical part 10 is pivoted at its upper end 11 to a sliding bar 12, which sliding bars 12 are all supported in 60 cross-bars 13 and 14, which are secured to the upper part of the frame. Each of these sliding bars 12 is provided with one or more lugs 15, for the purpose of operating the punch rods or pins, as hereinafter more fully described. 65

16 are four bars, each one of which carries at its forward end a punch rod or pin 17 18 19 20. These bars 16 are supported by and slide in a cross-bar 21 and a guide 22.

23 are four shorter bars under the forward 70 ends of the bars 16, each of which carries at its forward end a punch rod or pin 24 25 26 27. 28 is another sliding bar at one side of the bars 23, and this bar carries a punch rod or pin 29. All of these bars 23 and 28 are 75 supported by and slide in the cross-bar 21.

30 31 32 33 34 are cross-bars, one of which is permanently secured to each one of the sliding bars 23 and 28, and 35 36 37 38 are four other cross-bars, one of which is secured 80 to each one of the sliding bars 16. The ends of these bars 30 to 38 are recessed, and are arranged in slides and guides 39, which are provided with partitions 40.

41 are springs arranged to act upon the ends 85 of the cross-bars 30 to 38 and return them to their normal position after they have been forced forward.

42 is a block through which the pins 17, 24, and 29 pass loosely. Each of these pins is 90 provided with a fixed collar 66, arranged to come in contact with the back side of the block 42.

43 is a punch rod or pin, which is permanently secured to the block 42. 95

44 are springs, which encircle rods which are permanently secured to the plate 47, which springs act upon the block 42 and return it to its normal position after it has been moved forward.

45 is a bracket secured to the frame. 46 is a plate secured to the bracket 45, which plate is provided with holes to receive the punch rods or pins.

47 is a plate secured by screws to the plate 46, washers being placed between the two plates to provide a space for the passage of the paper to be operated upon.

5 All of the punch-pins pass through a plate 64, which is supported by the frame, and in their normal position their forward ends enter the plate 47.

48 is a rock-shaft, the ends of which are 10 pivoted in the posts 5.

49 are arms rigidly secured to the rock-shaft 48.

50 is a cross-bar suspended from the arms 49 by the rods 51. Each lever 7 is provided 15 with a notch on its under side to receive the cross-bar 50, and the depths of the notches in these levers 7 vary.

52 is a cylinder supported in brackets 53. There are two of these cylinders—one on each 20 side of the center of the machine.

54 are short cylinders provided with heads at each end, which cylinders enter the cylinders 52 a short distance.

55 is a spring located in the cylinder 52, arranged 25 to act upon one of the cylinders 54. There is a similar spring in the other cylinder 52.

56 are arms secured at their lower ends to the rock-shaft 48. Their upper ends are arranged 30 to engage with the outer heads of the cylinders 54.

57 are two feed-wheels, which are provided with sharp teeth, for the purpose of feeding the strip of paper through the machine.

58 are two wheels, each provided with a rubber surface, between which wheels 57 and 58 the paper passes.

59 are pawls pivoted one to the front end of each of the short cylinders 54. These pawls 40 engage with ratchet-wheels 65 on the lower ends of the shafts which carry the wheels 57, which shafts are supported in long bearings 60, which are supported by the bracket 45.

61 is a bar supported by two levers 62, which 45 levers 62 extend back to and are pivoted upon the shaft 9. These arms or levers 62 are also provided with notches to engage with the bar 50.

63 is a spring, one of which is provided for 50 each of the levers 7 and for the bars or levers 62.

The operation is as follows: To indicate a dot at the beginning of a letter requires the pins 43 and 29. To indicate a dash at the beginning 55 of a letter requires the pins 43 and 24. Thus the pin 43 must be used at the beginning of every letter. If the pin 29 be pushed forward, it will carry with it the pin 43, because the collar on 29 will cause the block 42 to move, and the pin 43 is fast to this block, and these two pins being one over the other perforations made by them will indicate a dot. If the pin 24 be moved forward, it will carry the block 42 along, the pin 43 moving with it, and the pins 43 and 24 being diagonal with each other their perforations 60 will indicate a dash. Each of the bars 12 is

operated by one of the keys 7, and each bar 12 is to be provided with lugs 15, sufficient in number and properly arranged to operate 70 the pins brought into use in making the perforations required for the letter to be indicated.

For example, F requires a dot, a dash, and a dot, and then there must be a space after the last dot to show that the letter 75 has been completed. Therefore when the F-key is struck, the pins 43 and 29 to indicate a dot, the pins 17 and 25 to indicate a dash, and the pins 19 and 26 to indicate another dot, must all be operated simultaneously, and then the paper must be moved beyond the pins, so as to leave a space after the perforations.

To do this the proper bar 12 must be provided with lugs to act on the bars 30, 35, and 32, 37 and 33 at the same 80 time, and then all the perforations required for the letter F will be made, because the bars last mentioned are connected with the sliding bars, which carry the pins to be operated.

After these perforations have been 85 made the paper must be moved far enough to carry all the last-made perforations beyond the pins and provide a space. The paper is moved by the pawls 59 and wheels 57, and the distance the paper moves is determined by 90 the depth of the notch in the lever which is operated.

When one of the levers 7 descends, the shaft 48 will be rocked through the rods 51 and arms 49, and the arms 56 will force the cylinders or plungers 54 into the cylinders 52, which will carry the pawls 59 back, the distance which they are moved depending 95 on the distance which the lever descends.

When the lever is released, the springs in the cylinders 52 will act on the cylinders or 100 plungers 54, forcing them forward with the pawls 59, which, being engaged with the ratchet-wheels 65, will cause the wheels 57 to rotate, carrying the paper along the proper distance.

The pointed teeth on the wheels 57 will engage 105 with the rubber on the wheels 58. A double space can be provided for at the end of each word by depressing the bar 61, and the arms or levers 62 will engage with the bar 50, rocking the shaft 48, and causing the plungers 54 110

to enter the cylinders 52, and when the spacing-bar 61 is released the action of the springs in the cylinders 52 will cause the pawls to operate upon the ratchet-wheels, as before, moving them one notch. I have not provided 115 any keys for the letters J and L. To make the perforations for the letter J, the space-bar 61 is to be held down. Then perforations for the letter N are to be made twice. Then the space-bar 61 is to be released, and the paper 120 will be moved the proper distance. To make the letter L, the space-bar 61 is to be held down. The perforations for the letter I are to be first made and followed immediately by the perforations for the letter M. Then by releasing the space-bar 61 the paper will be moved the proper distance. By the use of 125 the space-bar alone the feed-wheels will be moved one notch. When perforations are 130

made which indicate dots, the feed-wheels will be moved two notches. When perforations are made which indicate dashes, the feed-wheels will be moved three notches.

5 A full-sized machine may be about ten inches long, about three inches wide at the back, eight inches in front, and about four inches high. The parts are to be made of metal, and must all be made strong and of 10 good workmanship, the best of steel being used for the working parts.

What I claim as new, and desire to secure by Letters Patent, is as follows:

15 1. In a perforating-machine for automatic telegraphing, the combination of a series of movable perforating-pins for punching parallel rows of perforations, pin-operating devices, a series of keys for actuating the pin-operating devices, and each of which in its 20 movement advances two or more of the perforating-pins, a rotating wheel having teeth to punch a center line of perforations, and means for rotating the wheel by the movement of the keys, substantially as described.

25 2. In a perforating-machine for automatic telegraphing, a series of keys, as 7, in combination with a corresponding series of sliding

bars 12, each operated by one of the keys, a number of sliding bars each carrying a perforating-pin, cross-bars, one connected with 30 each of the sliding bars which carry the perforating-pins, and lugs on each of the sliding bars 12, arranged to simultaneously operate the desired number of pins, substantially as 35 and for the purposes specified.

3. In a perforating-machine for automatic telegraphing, the cylinders 52, in combination with the cylinders or plungers 54, springs 55, pawls 59, ratchet-wheels 65, feed-wheels 57, a series of keys 7, and intermediate 40 devices between the keys and plungers 54 for operating the same, substantially as specified.

4. In a perforating-machine for automatic telegraphing, a series of keys, as 7, and a corresponding series of sliding bars 12, and lugs, 45 as 15, on the bars 12, in combination with a series of bars, each carrying a perforating-pin and each secured to a cross-bar, and springs 41, arranged to act on such cross-bars, substantially as specified.

FRANK D. MACK.
